UNITED STATES PATENT OFFICE

2,570,314

COMPACT

Eve Brand, New York, N. Y.

Application May 5, 1949, Serial No. 91,531

3 Claims. (Cl. 132—83)

1

This invention relates generally to the cosmetic art, and more particularly to an improved cosmetic compact.

As is well known in the art, most cosmetic compacts are provided with a small mirror usually fitted into the inner surface of the lid of the compact. When the lid is closed, therefore, the outer surface thereof is disposed adjacent the powder or rouge and the applicator pad used in conjunction therewith. As the compact is carried in the user's handbag various bumps and jars tend to shake loose small particles of powder which come to rest upon the surface of the mirror, interfering with the reflective properties thereof. Since the powder is generally of extremely fine grain, it tends to smear over the surface of the mirror very readily, necessitating relatively frequent cleaning.

It is, therefore, among the principal objects of the present invention to provide a compact in which the above mentioned disadvantage has been substantially eliminated.

Another object of the present invention herein lies in the provision of a compact in which the mirror is fully protected from the effects of powder contained therein when the compact has been closed.

Another object of the present invention herein lies in the provision of a compact in which the mirror may be used when the compact is in a closed position, for the application of lipstick and the like, there being no danger of spilling the contents of the compact during this procedure.

Still another object of the present invention lies in the provision of a compact in which the mirror is rotatably mounted within the lid thereof, and which automatically pivots upon the opening or closing of the lid.

Another feature of the invention lies in the fact that the mirror element is resiliently urged into position when the compact is closed.

A further object of the present invention lies in the provision of a compact having the above mentioned advantages in which the cost of manufacture may be of a relatively low order with consequent wide sale, distribution, and use.

These objects and features, as well as other incidental objects and advantages, will become more fully apparent during the course of the following disclosure, and be pointed out in the appended claims.

On the drawing similar reference characters have been employed to designate corresponding parts throughout the several views.

Figure 1 is a front view of the embodiment, partly broken away to show internal detail.

2

Figure 2 is a right side elevational view.

Figure 3 is a rear elevational view.

Figure 4 is a view in perspective of the embodiment showing an opened position thereof.

Figure 5 is an enlarged vertical sectional view as seen from the plane 5—5 on Figure 4.

Figure 6 is an enlarged fragmentary vertical sectional view as seen from the plane 6—6 on Figure 1.

Figure 7 is an enlarged fragmentary vertical sectional view as seen from the plane 7—7 on Figure 1.

The device, generally indicated by reference character 10, includes broadly a main body element 12, a lid element 14, and a mirror element 16.

The main body element 12 is of substantially box-like construction, and includes a bottom wall 18, side walls 20, 22, 24 and 26, and an upper wall 28. Disposed in the surface of the upper wall 28 and extending downwardly substantially to the bottom wall 18 is a powder retaining recess 30, in which both powder 32 and a puff 34 may be disposed. A foraminous member 36 may be disposed within the recess in a well known manner when the powder employed is to be used in a finely divided state, although the same may be omitted where the powder is inserted into the compact in cake form.

The lid element 14 is of construction generally similar to that of the main body element 12, and includes a top wall 38, a lower wall 40, side walls 42, 44, 46, and 48. The hinge member 50 pivotally interconnects the lid element 14 to the main body element 12, thus enabling it to be opened and closed readily. The lid element 14 is maintained in a closed position by any suitable means as for example the sliding member 52 which engages the stud 54 on the wall 20.

The lid element 14 has disposed therein a shaped orifice 56 which corresponds generally in shape to the recess 30, although, of course, not necessarily so. The orifice 56 extends from the top wall 38 through the lower wall 40, both walls being cut out in order that the mirror element may be pivotally disposed therein.

The mirror element 16, as has been mentioned, is pivotally secured within the shaped orifice 56, and includes the mounting member 58, in which is disposed a mirror member 60. The mirror member 60 may be of the conventional type having a silvered inner surface 62, while the mounting member 58 is preferably formed from a single stamping, the side portions 64, 66, 68 and 70 of which may be bent about the mirror to retain the same therein.

Extending from the side portions 66 and 70 is a pair of short pins 72 and 74 each of which is engageable in an orifice in each of the bounding surfaces of the orifice 56, thereby providing for the pivotal mounting of the mirror element 16. The pin 72 is connected to one end of a small torsion spring 76 which tends to exert a counter clockwise torque upon the pin as seen on Figure 6. The other terminus of the spring 76 is suitably fixed to any convenient portion of the lid element 14, as for example the inner surface of the lower wall 40. The pin 74 has attached thereto a flexible connecting member 78 which extends through a small orifice 80 in the lower wall 40 (see Figure 4), and is secured to the upper wall 28, a short distance away from the hinge member 50. The length of the connecting member 78 is such that when the device is opened to the position shown in Figure 4 the mirror may be rotated about an axis through the pins 72 and 74 against the action of the spring 76. When the device is moved to a closed position, as indicated on Figures 1, 2 and 3, the connecting member 78 becomes slack, thereby allowing the spring 76 to rotate the mirror in the opposite direction whereby when the lid element 14 has contacted the main body element 12 the mirror member 60 is facing outwardly of the device. Upon reopening of the device, the connecting member 78 again becomes taut, and the mirror is rotated clockwise as indicated by the dot dash line portion on Figure 5 so that the mirror member may be facing the user when the device is in the position shown on Figure 5. In order that the mirror does not continue to rotate when it has reached the proper position, a small projection 82 is provided on the side portion 66 which engages the lid element 14, further opening of the compact and further rotation of the mirror being thereby prevented.

It may thus be seen that I have invented a novel and useful improved cosmetic compact structure, in which the mirror element is at all times completely shielded from the effects of powder which may loosen from the surface of the powder puff or the powder recess. The device is substantially foolproof, is simple in operation, and may be produced at an extremely low manufacturing cost. The device requires no special skill in operation, being completely automatic.

I wish it to be understood that I do not consider the invention limited to the exact details of structure shown and set forth in the specifi-

cation, for obvious modifications will occur to those skilled in the art to which the present invention pertains.

I claim:

1. Cosmetic compact construction comprising: a main body element, a lid element hingedly connected to said body element, and a mirror element; said lid element having an aperture disposed therein; said mirror element being pivotally disposed within said aperture; and means to pivot said mirror upon movement of said lid element with respect to said main body element; said means including a resilient component.

2. Cosmetic compact construction comprising: a main body element, a lid element hingedly connected to said body element, and a mirror element; said lid element having an aperture disposed therein; said mirror element being pivotally disposed within said aperture; and means to pivot said mirror upon movement of said lid element with respect to said main body element; said means including a torsion spring.

3. Cosmetic compact construction comprising: a main body element, a lid element, and a mirror element; said lid element being pivotally associated with said main body element; said mirror element being pivotally associated with said lid element; and means associated with said main body element serving to rotate said mirror element with respect to said lid element when said lid element is moved with respect to said main body element, said means including a flexible elongated connecting member.

EVE BRAND.
